UNITED STATES PATENT OFFICE.

GEORGE G. REEVES, OF SHREVEPORT, LOUISIANA.

OUTLET VALVE.

Application filed February 6, 1926. Serial No. 86,504.

This invention relates to outlet valves, especially adapted for use on tank cars and similar containers.

The object of the invention is to provide a valve for this purpose which is simple and inexpensive in its construction, direct in its action, and easy to operate; and more especially to provide a valve for tank cars, which may be opened or closed from the outside of the car without opening the dome, or otherwise gaining access to the interior of the container.

By virtue of the construction herein described, the valve may be closed after the car has been filled, or opened to empty the car in far less time than the style of valve heretofore used. It is strong and durable, and direct positive pressure is applied both in opening and closing the same.

The specific construction of the invention and the advantages thereof will be more fully explained in the following detailed description, which is to be read in connection with the accompanying drawing illustrating the preferred form thereof.

In the drawing:

Figure 1 is a front elevation of the invention.

Figure 2 is a side elevation thereof.

Figure 3 is a vertical section taken substantially on the line 3—3 of Figure 2.

Figure 4 is a horizontal section taken substantially on the line 4—4 of Figure 3.

Figure 5 is a horizontal section taken substantially on the line 5—5 of Figure 3.

The invention is illustrated in connection with a portion of a tank car or similar container 10, having an outlet 11 in its bottom. Leading from the outlet is a substantially cylindrical housing 12 having an outwardly turned flange 13 at its upper end, which is riveted or otherwise secured to the bottom of the container, as shown at 14. The interior of the housing 12 is formed at its upper end with a conical face 15 for receiving the conical lower face of the valve 16, and a bushing 17 secured in the upper portion of the housing 12 forms a seat for the valve.

The valve 16 is formed with an upwardly projecting stem 18, which extends through an opening in a yoke 19, and is secured therein by a rivet 20 or the like. The end of the yoke 19 is pivoted to ears 21 integral with, or fastened to, the flange 13, so that the valve and yoke may be swung inwardly, as indicated by the dotted lines in Figure 3.

The interior of the housing 12 is formed at one side with a flat wall, as shown at 22, or vertical rib is formed on the outside, in which is formed a dove-tailed channel 23 for receiving and guiding a vertical rack bar 24. In case the vertical rib is formed on the outside of the housing 12, then the lower portions 39 and 40 of the housing are enlarged so as to permit the insertion or withdrawal of the rack bar 24 therethrough in assembling or taking apart. The inner face of this rack bar is formed with ears 25, which are connected by a link 26 to ears 27 which project downwardly from the bottom face of the valve 16. The opposite face of the rack bar 24 is formed with teeth 28, which are adapted to mesh with teeth 29 formed on a transversely disposed mandrel 30. The housing 12 is enlarged at one side, as shown at 31, and formed with a transverse bore 32 in which the mandrel 30 is rotatably mounted. The housing is also provided with a stuffing box 33 surrounding the outer portion of the mandrel to prevent possible leakage.

The outer end of the mandrel is square or polygonal, as shown at 34, and adapted to receive a handle 35 by means of which the mandrel may be rotated to open or close the valve 16. The handle 35 is preferably made easily and quickly removable. A disk 36 is mounted on the end portion 34 of the mandrel inside of the handle 35, and is provided with a series of holes 37, so that whatever the position of the disk, one of the openings 37 will be in position to be connected by a car seal to an eye 38 formed on the adjacent part of the housing 12. Other eyes 38^a may also be provided on the housing for attaching small chains, which will be connected to removable parts to prevent loss of the same.

The lower end of the housing 12 is internally threaded, as at 39, so that a pipe or hose may be connected thereto for discharging the contents of the container. During transit, a cap may be inserted in the end of the housing as an additional precaution against loss of the contents. It is desirable to provide the lower end of the housing 12 with an external flange 40, which may be used in connection with improved coupling devices for connecting a pipe thereto.

From the foregoing description, it will be understood that the valve may be opened or closed by simply rotating the mandrel 30.

Thus, a strong, direct and positive pressure is applied both in opening or closing, and the valve operating means is always accessible. While I have shown and described 5 the preferred embodiment of the invention, it is obvious that various modifications may be made in the details of construction, and in the arrangement of various parts thereof without any material departure from the 10 salient features of the invention as expressed in the claims.

What is claimed is:

1. In combination, a housing adapted to be secured to a liquid container and having 15 an outlet passage therethrough, a valve adapted to close said passage, said housing being formed at one side with a longitudinal channel, and a transverse bore adjoining the channel, a rack bar guided in said channel, 20 means connecting the rack bar with the valve for operating the latter, a mandrel in said bore and provided with teeth meshing with the rack bar, the overall diameter of the toothed portion of the mandrel being not 25 greater than the bore, so that the mandrel may be inserted endwise into the bore and retained therein by the teeth of the rack, and means for rotating the mandrel to advance the rack and open the valve.
2. In combination, a housing adapted to be secured to a container and having an outlet passage therethrough, a valve for closing the inner end of said passage and formed with an inwardly projecting stem, a yoke 30 pivoted at one side of the passage and secured to said stem, said housing being formed with a longitudinal dovetailed channel in its inner face and having an extension outside said channel with a transverse bore 35 therein, a rack bar reciprocable in said channel, a link connecting the rack bar to the valve, a mandrel in said bore having teeth meshing with said rack bar, and means con-

nected with said mandrel for rotating the same to open or close the valve. 45

3. In combination, a housing adapted to be secured to a container and having an outlet passage therethrough, a valve adapted to close said passage, said housing being formed with a longitudinal dovetailed channel in its inner face and having an extension outside said channel with a transverse bore therein, a rack bar guided for reciprocation in said channel, a link connecting the rack bar to the valve, a mandrel in said bore and 50 provided with teeth meshing with the teeth of the rack bar, and means connected with the mandrel for rotating the same to reciprocate the rack bar, whereby to open or close the valve. 55

4. In combination, a housing adapted to be secured to a container and having an outlet passage therethrough, a valve for closing said passage, a rack bar guided for movement longitudinally of the housing, a link 60 connecting the rack bar to the valve, a mandrel having teeth meshing with the teeth of the rack bar, means for rotating the mandrel to actuate the rack bar, whereby to open or close the valve, and means on the mandrel 70 and the adjacent part of the housing to which a car seal may be attached.

5. In combination, a housing adapted to be secured to a container and having an outlet passage therethrough, a valve for controlling said passage, a mandrel rotatably mounted transversely of the housing, means operable upon rotation of the mandrel to open or close the valve, a disk keyed to said mandrel and having a series of holes near its 75 outer edge, and an eye on the adjacent part of the housing and adapted, in conjunction with one of said holes, to receive a car seal. 80

In testimony, that I claim the foregoing as my own, I have hereto affixed my signature.

GEORGE G. REEVES.
